UNITED STATES PATENT OFFICE.

MARY E. SCHILZ, OF PHILADELPHIA, PENNSYLVANIA.

DESIGN FOR A MANICURE-TOOL.

SPECIFICATION forming part of Design No. 29,019, dated July 12, 1898.

Application filed June 20, 1898. Serial No. 684,010. Term of patent 7 years.

To all whom it may concern:

Be it known that I, MARY E. SCHILZ, a citizen of the United States, residing in Philadelphia, Pennsylvania, have invented a certain new and useful Design for a Manicure-Tool, of which the following is a specification.

My design for a manicure-tool is fully illustrated in the accompanying drawing, which illustrates the tool in perspective.

The essential feature of the design is the cylindrical handle having a grooved portion at one end and an enlarged portion at the opposite end.

A is the tubular handle portion, cut away at

a, forming a semicircular rounded end *a'*. At the opposite end of the handle is a quadrangular enlargement *b*, tapered at the end *b'*.

I claim—

The design for a manicure-tool as herein described and as illustrated in the accompanying drawing.

In testimony whereof I have signed my name to this specification in the presence of two subscribing witnesses.

MARY E. SCHILZ.
